UNITED STATES PATENT OFFICE

THOMAS HERBERT CLARK, OF MARION, OHIO, ASSIGNOR TO THE MARION STEEL BODY COMPANY, OF MARION, OHIO, A CORPORATION OF OHIO

DUMPING UNIT FOR TRUCKS

Application filed January 29, 1930. Serial No. 424,371.

This invention seeks to provide a simple, compact, inexpensive and efficient mechanism whereby a dumping body may be raised and lowered and will be firmly supported when not in the dumping position. The invention also seeks to provide a dumping unit which may be readily applied to any standard dumping truck chassis. The invention is illustrated in the accompanying drawings and will be hereinafter first fully described and then more particularly defined in the appended claims.

In the drawings:

Figure 1 is a side elevation, with parts broken away and parts in section, of so much of a dumping truck as is necessary to an understanding of my invention,

Fig. 2 is a horizontal section on the line 2—2 of Fig. 1,

Fig. 3 is a detail section on the line 3—3 of Fig. 2, and

Fig. 4 is a detail section on the line 4—4 of Fig. 2.

The truck chassis, indicated at 1, may be of any approved dimensions and construction. In carrying out the present invention, there are provided side members or sills 2 which are strong wooden timbers and are adapted to rest upon the side bars of the chassis, as shown in Fig. 1. The rear upper corners of these beams are beveled or cut-away, as indicated at 3, whereby they accommodate the varying angular position of the dumping body or box 4 and also furnish a support against which the bottom of the body may bear when in the dumping position. The rear extremities of the beams or side bars 2 are connected transversely by an angle bar 5 which projects laterally beyond the beams and has its ends secured to brackets 6 which are also secured to the outer sides of the beams, as clearly shown in Fig. 2. The brackets 6 have openings formed therethrough to accommodate a fulcrum rod 7 which extends across the entire width of the dumping unit and is received at its ends in bosses 8 on the outer sides of fulcrum brackets 9 which extend upwardly from the brackets 6 and are secured to the outer sides of rails or angle bars 10 which, in turn, are

firmly secured to the bottom of the dumping body 4. The body 4 may be of any desired detailed design and dimensions and is provided adjacent its front end with transverse props or rests 11 which are adapted to rest upon the upper sides of the side bars 2, as shown. The brackets 9 constitute rockers which may swing about the fulcrum rod 7 and any approved means for preventing lateral movement of the rocking brackets along the fulcrum rod may be employed, the drawings illustrating cotter pins as a matter of convenience. Near their front ends, the side bars or beams 2 have notches, indicated at 12, formed transversely in their upper edges and clips or U-bolts 13 are seated in said notches to span the respective side bars and extend down to points below the sills of the chassis, as will be understood, clip plates 14 being fitted upon the U-bolts below the sills 1 and nuts 15 being mounted upon the extremities of the bolts to be turned home against said clip plates whereby the beams may be readily and firmly secured upon the sills. Secured to the outer sides of the respective beams 2 adjacent the U-bolts 13 are plates 16 which project above the beams and have their outer edges turned slightly outward whereby the plates serve as reinforcements for the beams and also guide the dumping body into proper position over the beams as it is lowered after a dumping operation.

Secured to the inner sides of the beams 2, between the ends of the same, are angle bars 17 which have their horizontal webs disposed along their upper edges and projecting inwardly with respect to the beams. Secured to and upon the front ends of these side angle bars 17 is a transverse angle bar 18 which serves to resist spreading of the side members of the unit and also constitutes a support for the front end of the cylinder 19 which forms a part of the operating mechanism. Extending transversely through the rear ends of the side angle bars 17 and through the beams 2 is a shaft or rod 20 upon which the rear end of the cylinder 19 is supported. To mount the rear end of the cylinder upon the rod or shaft 20, a sleeve 21 is fitted about the shaft and is formed with a half bearing or

seat 22 in its upper edge within which the end of the cylinder rests, a clamping band 23 being fitted over the cylinder to mate with the seat 22, as shown clearly in Fig. 3, and securing bolts 24 being fitted through mating lugs on the seat and the band whereby to firmly secure the clamping band over the cylinder. Mounted upon the rod or shaft 20 adjacent and at the sides of the cylinder are segments 25 which form supports and guides for chains 26, each segment having a single tooth, indicated at 27, between its ends upon its arcuate edge adapted to engage links of the chain 26 and thereby center the chain upon the segments during the operation of the apparatus. Each chain at one end is connected to a crank 28, which is fitted upon the shaft or rod 20 alongside a segment 25, and at the opposite end is secured to a crosshead 29 which is carried by the rear end of a piston rod 30 extending through the rear head of the cylinder 19 and fixed to a piston 31 slidably mounted within the cylinder. The crosshead 29 is entirely free of all parts except the piston rod and the chains and is, therefore, permitted to rock in a transverse vertical plane and accommodate possible variations in the movement of the respective chains as the dumping body is raised or lowered. To the free end of each crank 28 are pivoted the lower ends of links 32 which have their upper ends pivoted to the side rails 10 which are secured to and extend longitudinally of the dumping body. If the piston 31 be driven rearwardly, the motion of the same will be transmitted through the piston rod to the crosshead and thence to the chains 26 so that the segments 25 which rock about the shaft or rod 20 and the cranks 28 will be swung upwardly, as will be understood upon reference to the dotted lines in Fig. 1. When the cranks 28 swing upwardly, the links 32, of course, are moved upwardly and the dumping body is lifted so that it rocks about the fulcrum rod 7 as a pivotal center. The load will, consequently, be discharged from the body and if the force moving the piston be removed the weight of the body will act by gravity to effect a return movement of all the parts and set the body to receive another load. It will be readily noted that the parts are so disposed that a dead center cannot occur, the segments 25 serving to maintain the chains in a properly curved line so that their end links will be in the proper angular relation to the crosshead and the cranks respectively to respond to the movement of one and impart movement to the other without any tendency to bind or pull either out of proper position.

The piston 31 is operated by fluid pressure and to that end a pump, indicated at 33, is disposed below the front end of the cylinder and is connected with the front end thereof through a pipe 34 which provides for a flow of oil or other fluid from the pump to the

front end of the cylinder to act upon the piston and drive the same rearwardly. The outlet from the cylinder is disposed near but in advance of the rear end thereof and is connected by a pipe 35 with the casing of the pump so that, when the pump is operating, a circulation of fluid from the rear end of the cylinder to the front end of the same through the pipe 35, the pump and the pipe 34 will be set up. The pump is supported from the cross bar 18 by a U-shaped hanger 36 having its ends secured rigidly to the cross bar, as shown in Fig. 4, and passing under the pump casing so as to support the same. The pump is preferably a well known gear pump and is operated through a shaft 37 extending to the motor of the vehicle which is not shown in the drawings as, in itself, it forms no part of the present invention. The pump is also equipped with a choke valve controlled through a rod or other device, indicated at 38, and extending to the front of the vehicle where it may be easily manipulated by the operator. When the pump is operating, the oil or other fluid will be forced into the cylinder and accumulate in front of and bear upon the piston so that the latter will be forced rearwardly to actuate the connections with the dumping body, as previously described. If it be desired to hold the dumping body in the raised position, the choke valve is closed so that the liquid cannot set up a return flow from the cylinder but will be held therein and as it is of some non-compressible fluid the dumping body will be firmly supported and held in the dumping position. When the dumping body is fully raised, the piston will be driven beyond the outlet port of the cylinder and if the pump then continues to operate it will effect a continuous circulation of the fluid but will not have any effect upon the piston and raising mechanism, except that the pressure exerted on the piston will be constant and will prevent its return. If the operation of the pump should cease with the choke valve open, the weight of the dumping body will, of course, return it to its lower carrying position, as previously stated and as will be understood.

The front end of the cylinder is supported firmly upon the cross bar 18 and the front head 39 is in the form of a plug fitting within the end of the cylinder and welded thereto so that it will have ample strength to resist the pressure to which it is subjected in use. The head is formed integral with a bracket 40 having lateral wings which bear against the vertical web of the cross bar 18 and are bolted thereto, as shown in the drawings. The cylinder is thus very firmly supported so that it will remain in its proper operative position and the piston may move readily without binding at all times.

From the foregoing description, taken in connection with the accompanying draw-

ings, it will be seen that I have provided an exceedingly simple, compact and efficient mechanism whereby a dumping body may be readily operated. The units comprising the side bars or beams 2 and the parts connected therewith obviously may be assembled independently of the truck chassis and may be built upon plans which are drawn in conformity to the particular chassis upon which any given unit is to be mounted. The weight of the unit will hold it firmly upon the chassis so that fasteners other than the clips 13 will ordinarily be unnecessary but, if desired, the cross bar 5 may be connected to the sills of the chassis either directly or through intermediate brackets. By utilizing continuous beams 2 of wood, I provide a substantial elongated support for the sides of the truck body and all tendency of the body to sag between its ends under load is overcome, this sagging or binding of the dumping bodies intermediate their ends being a serious objection to many, if not all, of the dumping trucks now in use.

Having thus described the invention, I claim:

1. A dumping unit for vehicles comprising a pair of beams, a dumping body mounted upon the beams for rocking movement about the rear ends of the same in a vertical plane, a cross bar connected with and disposed between the beams in advance of the rear ends thereof, a cylinder secured at its front end upon said cross bar, a transverse rod mounted fixedly in the beams at the rear of said cross bar and below the cylinder, a sleeve engaged about said rod and supporting the rear end of the cylinder, a piston mounted in the cylinder, means for operating the piston by fluid pressure, cranks mounted upon the fixed transverse rod to turn thereon at the sides of the cylinder, links connecting the respective cranks with the dumping body, a crosshead connected with the piston at the rear of the cylinder and above said rod, segments mounted on the fixed transverse rod at the sides of and connected with the cranks, and flexible connections between the crosshead and the cranks, said connections passing forwardly from the crosshead over and being supported by the segments.

2. A dumping unit for vehicles comprising a frame including a transverse angle bar, a dumping body mounted for rocking movement about the rear end of the frame in a vertical plane, a cylinder, a head welded to the front end of the cylinder and having a bracket disposed against and secured to the cross bar of the frame, a transverse rod secured rigidly in the frame below the rear end of the cylinder, a sleeve fitted on said rod and having a seat in which the rear end of the cylinder rests, a clamping band passing over the cylinder and mating with and secured to said sleeve, rocking segments

mounted upon the rod at the sides of the cylinder, a fluid-driven piston within the cylinder, a crosshead at the rear of the cylinder connected with said piston, chains connected at their rear ends to the crosshead and passing over and supported by said segments, cranks mounted upon the rod at the sides of and connected with the respective segments and having the front ends of the chains connected thereto, and links connect- 70
ing the cranks with the dumping body. 75

In testimony whereof I affix my signature.
THOMAS HERBERT CLARK. [L.S.]
